UNITED STATES PATENT OFFICE

LOUIS D. SUMMERS, OF DECATUR, ILLINOIS, ASSIGNOR, BY MESNE ASSIGNMENTS, TO LEADER IRON WORKS, INC., OF DECATUR, ILLINOIS, A CORPORATION OF DELAWARE

BOILER

Application filed August 18, 1927. Serial No. 213,734.

My invention relates to heating boilers of a type normally used for heating buildings, an object being in this device to provide a convenient and practical organization in a boiler that will be economical to operate and so constructed as to be able to secure a maximum of heat transfer from the hot products of combustion to water that is being heated in the boiler.

10 A further object of my invention is to provide in a heating boiler a compact organization of boiler and economizer that will be convenient to move in parts and set up and easy to get through basement doors and the like without disassembling all parts of the boiler.

20 A further object of my invention is to provide in a unit boiler organization a section thereof so positioned and operatively connected with other parts of the boiler as to economically provide a greater area of contact with the hot products of combustion and a consequent greater efficiency and economy resulting from the boiler's use.

25 A further object of my invention is to provide in a hot water boiler having an economizer section, a combustion chamber adapted to economically and successfully burn oil, gas or coke with remarkable efficiency.

30 I attain the objects of my invention in the boiler described in the specifications here-with, recited in the claims and illustrated in the accompanying drawings in which like reference numerals indicate like parts in the 35 several figures.

Referring to the figures:

Figure 1 is a vertical section from front to back through the center of my boiler.

Figure 2 is a vertical section 2-2 of Figure 3.

Figure 3 is a side elevation of my boiler.

Figure 4 is a front view of my boiler.

Figure 5 is a horizontal section 5-5 of Figure 3.

45 Figure 6 is a horizontal section 6-6 of Figure 3.

Figure 7 is a top view of my boiler.

Figure 8 is a horizontal section 8-8 of Figure 3.

50 Referring to the construction of my boiler

and the normal method of operating the same, I provide a combustion chamber —1— communicatively connected by pipes through passages adapted to accommodate the movement of the products of combustion from the combustion chamber in a manner that will accomplish the maximum of heat transfer from the hot gases to the water —2— before they leave the outlet gas chamber —3—.

In order to accomplish the purpose of my invention, I provide in cooperative combination a main boiler section —4— and economizer section —5—, which sections are detachably and operatively built together.

It was once thought by engineers that in order to get the greatest efficiency from the products of combustion that a strong draught was needed to cause a speedy movement of the products of combustion all the way from the combustion chamber to the outlet flue and in some kinds of fuel and in some situations where for instance, soft coal may be used as a heating fuel such a point of view may be well taken.

However, as a result of recent experiments and developments in the line of domestic heating equipment, it has been found when using oil, gas and coke as fuel, that it is possible to so organize heating equipment as to effectively and most economically conserve the heat from the fuel and obtain therefrom a remarkably great percentage of efficiency by carefully and scientifically providing for the movement of the products of combustion at such rates and through such passages as will cause them to give up the greatest possible percentage of their heat before they leave gas outlet —6— adapted to be connected with a building flue.

In order therefore to get the above mentioned desired results with my boiler, I so construct my boiler as to surround the combustion chamber —1— with a water leg —7— communicatively connecting a central water chamber —8— of an upright heat economizer section —5— of the boiler with water leg —7— and water or steam chamber —9— through lower water passage —10— and upper water or steam passage —11—.

Between the main boiler section —4— and

economizer section —5— I provide a central gas chamber —12—.

About combustion chamber —1—, I provide a large heating surface with which the water —2— comes in contact but if I permitted the hot products of combustion to flow from flue —13— immediately to the house flue they would be discharged and lost while still holding the temperature of a very high degree varying from 500 to perhaps 1500 degrees which would be as has been in the past, a great loss of heating energy.

But in order to conserve this normally lost energy for more extensive heating purposes and for more economical operations of the heating plant, I conduct the hot products of combustion coming from the flue —13— first through a central gas chamber —12— where they come in contact with sheet —15— of the economizer section forming the enclosing wall for central water chamber —8— of the economizer section —5—. From this central gas chamber the gases pass up through opening —16— into upper gas chamber —17— through a plurality of gas tubes —14— through which they settle to lower levels as they get cooler and as they settle they give up a greater percentage of their heat to the tubes causing the water in water chamber —8— to become heated thereby before the gases move out through lower gas chamber —3— to outlet —6— from which they pass into the building flue at a comparatively low temperature.

By this arrangement, I obtain what is known as the counterflow principle of heating water in a most remarkably efficient manner with a boiler and economizer organization that is compact, substantially made and economical to operate as well as convenient to move and set up.

There may be occasions when it would be desirable to provide for the hot products of combustion to pass directly into the building flue through an outlet —18— in order to create a temporary draught for quickly starting a fire in combustion chamber —1—, in which case damper —19—, preferably operated by thermostatic control, would be automatically closed within a predetermined time limit and cause the hot products of combustion then to be directed down through tubes —14— to lower gas chamber —3— and out to the building flue.

In a study of the drawings, it will be observed that I provide for the support of the coke —20— a grate —21— (when coke is used as a fuel) but when oil is used as a fuel the oil burner —22— may be used and grate —21— may be removed. Natural or artificial gas could be burned in a manner similar to the arrangement provided for burning oil.

When it is desired to look into the combustion chamber or put coke therein, door —23— may be opened for this purpose and when

coke is used ash door —24— may be used as an ash clean-out door.

By observing Fig. 3 it will be noted that I provide along with flue —13— a similar flue —13'— spaced therefrom so as to throw the gases, when leaving the combustion chamber, in contact with a greater area of sheet —15— of economizer section —5— as the gases enter central gas chamber —12—. A clean-out hood —25— is provided above gas chamber —17— of the economizer section of the boiler while in addition to out-let —6— in lower gas chamber —3—, I provide other outlets —26— and —27— that may be more convenient in some situations for attachment to a building flue depending on the position the heating plant is required to sit in in relation to the flue.

When outlet —6— is connected with the building flue, then outlets —26— and —27— are closed with a suitable hood —28—.

Openings —29— and —30— may be used as convenient connections with water leg —7—.

When the boiler is assembled a pair of side plates —31— and —31'— are substantially held into normal operating position by a hood —32— as well as by rods connecting the two plates together indicated by numerals —33— and —34—. A draincock —35— is provided at the lower end of the casing surrounding water leg —7—.

For convenience and safety water gauge —36— is provided together with test valves —37— while a steam gauge —38— is used for determining steam pressure developed in the boiler.

A damper control device indicated by numerals —39—, —40—, and —41— and —42— may be satisfactorily used.

A floor pan —44— is used for the floor support of the boiler. Numeral —46— indicates a steam and water spud.

It will be observed that a return pipe connection 43— is provided in the base of central water chamber of the economizer section and when the cold water enters at this point the hot products of combustion at their lowest temperature start heating the cold water and as more cold water enters and the water already admitted becomes warmer, the warmer water rises in the central water chamber and establishes communication with water leg —7— of the main boiler through passage —10—; and thus is somewhat heated before it enters water leg —7— which encompasses the combustion chamber —1—. It is to be especially noted as the warmer water rises in central water chamber —8— that it is caused to rise more forcefully because of cold water displacing it than through the fact that it becomes heated.

The sheets —45— and —47— may be made parallel in order that all upright tubes may be made of equal length but the upper tube 130

sheet —45— over the central water chamber is inclined toward passage —11— connecting the two water compartments; thus to avoid air pockets under tube sheet —45— where the heating apparatus would be operated in connection with a hot water system. Numeral —47— indicates the lower tube sheet of the economizer section.

To those skilled in the heating art, it will be evident that certain minor changes may be made in the structure above disclosed without departing from the spirit and scope of my invention but the preferred arrangements of essential features of my boiler have been hereinabove described and illustrated in the drawings herewith.

Having thus described the nature of my invention, what I claim is:

1. A counterflow heating boiler comprising a pair of upright heating units operatively connected detachably by upper and lower water connections and separated by a gas chamber communicating with said units and disposed intermediate said units formed by detachable side plates extending between the units and a hood therefor, the first upright unit having a combustion chamber and a water space above said combustion chamber, the second upright and counterflow unit provided with a central water chamber, a detachable clean-out hood and an upper and lower gas chamber communicatively connected through gas tubes extending uprightly through the central water chamber, upper and lower tube sheets for said central water chamber of the counterflow unit; said upper tube sheet inclined to direct the hot water and steam through said upper water connection between the units to provide unrestricted movement of hot water and steam from under the upper tube sheet, outlets from the upper and lower gas chambers of the counterflow unit connected with the house flue; means for admitting cold water to the lower part of the cold water chamber of the counterflow unit and means for discharging hot water and steam from the top of said water chamber of the first unit.

2. A boiler of the character described comprising in integral combination a boiler unit including an upright combustion chamber encompassed by a water jacket and water chamber and an upright counter-flow economizer unit spaced from said first unit and provided with upper and lower gas chambers and a central water chamber, an intermediate gas chamber between said boiler unit and economizer unit in communication with both units and extending throughout the height of said units; said economizer unit and said boiler unit being connected with each other by upper and lower water connections and by intermediate detachable side plates engaged by a hood provided with a detachable clean-out cap and closing the top of said

upper gas chamber and said intermediate gas chamber; said intermediate gas chamber communicating with said upper gas chamber of the counterflow unit by a gas passage registering with the upper gas chamber of the counterflow unit and communicating with said combustion chamber of the first unit through hot gas passages disposed relatively lower than the gas passage leading to the upper gas chamber of the counterflow unit; said economizer unit provided with a plurality of upright gas tubes extending through the central water chamber thereof supportably secured to upper and lower tube sheets; upper and lower water connections for communicatively connecting the economizer water chamber with the water chamber of the boiler unit; said upper tube sheet inclined to meet and register with said water connection between the units; gas discharge flues connected with said upper and lower gas chambers of the counterflow unit and with the house flue and water intake and outlet connections for the water chamber.

3. A counterflow heating apparatus comprising in integral cooperative combination an upright boiler unit and a counterflow heat economizer operatively connected therewith as an integral unit by side plates so as to provide an intermediate gas chamber between the boiler and economizer extending throughout their height, an upper and a lower gas chamber in the economizer connected by a plurality of upright gas tubes supported by upper and lower tube sheets forming a central water chamber between the sheets; a central combustion chamber for the boiler unit surrounded by a water leg and water chamber; said water leg and chamber of the boiler communicating with said central water chamber of the economizer through upper and lower water pipes; said upper tube sheet inclined toward and registering with said upper water pipe to direct movement of water and steam there through from the economizer unit to the boiler unit; said combustion chamber communicating with said intermediate gas chamber through gas passages in a manner to discharge hot gases from the combustion chamber first into said intermediate gas chamber; said upper gas chamber of the economizer communicating with said intermediate gas chamber by a gas receiving aperture registering with said upper gas chamber of the economizer; a hood for said intermediate gas chamber and a detachable clean-out cap therefor registering above the economizer unit; gas discharge connections with said upper and lower gas chambers operatively connected with the house flue.

In witness whereof, I hereunto set my hand this 11th day of July, 1927.

LOUIS D. SUMMERS. 130
